(57) CLAIM

The ornamental design for the purse, as shown and described.

DESCRIPTION

FIG. 1 is a perspective view of a purse showing the new design in accordance with a first embodiment of the invention in a closed position.

FIG. 2 is a front view thereof in a closed position. The back view is a mirror image of the front view.

FIG. 3 is a left side view thereof in a closed position. The right side view is a mirror image of the left side view.

FIG. 4 is a top view thereof in a closed position.

FIG. 5 is a bottom view thereof in a closed position.

FIG. 6 is a perspective view thereof in an open position.

FIG. 7 is a front view thereof in an open position.

FIG. 8 is a back view thereof in an open position.

FIG. 9 is a left side view thereof in an open position. The right side view is a mirror image of the left side view; and,

FIG. 10 is a top view thereof in an open position. The bottom view is a mirror image of the top view.
